Des. 223,570
Patented May 9, 1972

223,570

FURNITURE SEAT

Donald T. Chadwick, 141 S. Barrington Ave.,
Los Angeles, Calif. 90044

Filed June 3, 1970, Ser. No. 23,277

Term of patent 14 years

Int. Cl. D6—02

U.S. Cl. D15—1

Fig. 1

Fig. 2

Fig. 3

Fig. 4

Fig. 5

FIG. 1 is a perspective view of one embodiment of my new design for furniture seat;

FIG. 2 is a rear elevation thereof;

FIG. 3 is a front elevation thereof;

FIG. 4 is a top plan view thereof;

FIG. 5 is a side elevation thereof as viewed from the side not exposed in FIG. 1;

FIG. 6 is a modified form of the furniture seat of FIG. 1 wherein the seat and backrest members are ovoidal;

FIG. 7 is a rear elevation thereof;

FIG. 8 is a top plan view thereof;

FIG. 9 is a side elevation thereof as viewed from the side not exposed in FIG. 6; and

FIG. 10 is a modified form of the seat of FIG. 1 wherein the length thereof has been extended to define a sofa.

I claim:

The ornamental design for furniture seat, substantially as shown.
